United States Patent Office.

C. A. HARPER, OF NEW YORK, N. Y.

Letters Patent No. 91,438, dated June 15, 1869.

IMPROVEMENT IN VELOCIPEDES.

The Schedule referred to in these Letters Patent and making part of the same.

To all whom it may concern:

Be it known that I, C. A. HARPER, of New York, in the county of New York, and State of New York, have invented a new and useful Improvement in Velocipedes; and I do hereby declare that the following is a full, clear, and exact description thereof, reference being had to the accompanying drawings, and to the letters of reference marked thereon.

Figure 1 is a plan or top view of a velocipede, showing my improvement attached thereto;

Figure 2 is a longitudinal elevation through the centre of the devices, showing the general arrangements of the parts; and

Figure 3 is a side elevation of the arm which is attached to the ratchet-wheel shaft, and the pawl or dog and spring connected therewith.

Corresponding letters refer to corresponding parts in the several figures.

This invention relates to an improvement in velocipedes, and is designed as an improvement upon the means for converting the reciprocating movements thereof into a rotary motion or movement; and

It consists in the combination and arrangement of its parts, as will be more fully described hereinafter.

To enable those skilled in the art to make and use my invention, I will proceed to describe its construction and operation.

A, in the drawings, represents the bed or platform of the machine, which may be of wood or metal, and of any desired proportions.

B B' represent the driving-wheels, which are to be secured to an axle, C, which extends across the machine at a right angle to the length of the platform A, and is supported in bearings formed in a frame which is secured to, and rises from such platform.

B² is the leading or guiding-wheel, which is attached to the rear end of the platform A, by means of an arched bar of metal, as shown in fig. 2 of the drawings.

C represents the driving-wheel axle above alluded to.

D represents the seat upon which the operator sits while riding upon and operating the machine. It is to be arranged directly in front of the driving-wheel axle, and so that the face of the person sitting thereon will be in the direction of the movements of the machine.

E represents a gear-wheel, which is to be placed upon the central portion of the driving-axle, and so arranged as to mesh into and drive another wheel, of about the same diameter, upon a counter-shaft.

F represents a gear-wheel which is to be secured to a counter-shaft, which has its bearings in the same frame to which the driving-axle is secured, and directly above the same, and at such a distance therefrom, that the two last-named gear-wheels will mesh into each other, and the former be driven by the latter.

G G' represent ratchet-wheels, which are to be placed upon the shaft last above named, i. e., the one to which the gear-wheel F is attached, they being arranged upon each side of such wheel, and firmly secured to such axle in any convenient manner. These wheels and axles may, however, be dispensed with, and the ratchet-wheels, one or more of them, be placed on the driving-axle.

H represents a lever, of which there are two, having upon their inner ends bosses, in which an aperture is formed through which the shaft of wheel F passes. These levers extend outward from the shaft, upon which they are placed, to a point just outside of the periphery of the ratchet-wheels, for which distance they are of considerable thickness; or they may have a socket secured to this portion of them, to receive the slide to which the dog or pawl is attached.

From the point where this slide enters the socket, formed in or upon these levers, they are to be reduced in thickness, and this reduced portion extends for some distance further in the same direction, for the purpose of allowing the outer end of the slide, to which the spring a is attached, to be secured thereto, and also the end of the jointed lever I, hereafter to be described.

I I represent jointed levers, which are to be placed upon the inner sides of the levers or arms H, their outer ends being pivoted to such levers, and their inner end pivoted together in such a manner, that in the operation of the machine they can be elevated at the points where they are pivoted together, and thus operate the levers H, and through them the ratchet-wheels G G'.

I¹ represents a slide, which is to be attached to the sides of the levers H H, there being one upon each lever. The inner ends of these slides are to be of any suitable form to prevent them from turning, and that will fit into the socket formed upon the arms H H, while their outer ends are to be round, for the purpose of receiving the spring a, as clearly shown in fig. 3 of the drawings.

I² represents a dog or pawl, which is to be pivoted to the flat or square portion of slides I¹ I', so that they can turn upon such pivots, and engage with the teeth upon wheels G G'.

K K represent connecting-rods, which are to have their upper ends attached to the jointed levers I I, their lower ends being pivoted to the ends of levers L L, to which the arms or rods L' L' are attached, for operating the machine.

L L represent levers, which are to be pivoted to the rear end of platform A, as clearly shown in fig. 2.

These levers are constructed in the form of a trough, having parallel sides for a portion of their length, and may have, in their bottoms, a hinged portion, capable of revolving upon its axis, as shown at b, fig. 2, and

which may be used to retain the levers in their most elevated position, by turning such hinged portion, so that one of its ends will rest upon the platform A.

L' L' represent rods, which are to be attached to the sides or some other portion of levers L L, and are to extend forward, in a horizontal direction, to a point midway of the operator's seat, or thereabouts, when they are to extend vertically for a distance which will bring them within easy access of the operator, when seated upon the machine.

M represents a frame or standard, which is to be secured to the platform A, and so arranged that it will span the levers L L, as shown in fig. 1.

N represents a roller or sheave, which is attached to the frame M in such a manner that a rope may be passed over it, and have its ends secured to staples or eye-bolts in the levers L L, the arrangement being such, that as one of the levers is forced downward, the other will, by the same movement, be drawn up, and thus be brought into a position for use.

O represents a cross-arm, which is to be placed upon the top of the frame P, and is for the purpose of guiding or steering the machine, its ends being provided with rings or holes, for the attachment of a cord or rope, which extends therefrom to the operator's seat for that purpose.

P represents the frame in which the guiding-wheel turns and is supported.

The operation of this mechanism is as follows:

The parts having been constructed and arranged as described, the operator seats himself upon the seat D, and grasps with his hands the ends of rods or arms L' L', and alternately raises and depresses them, or stands upon the reciprocating levers, alternately changing his weight from foot to foot; or two operators may

work together, one from the seat, the other standing on the levers, which operation communicates motion to the levers L L, and through them to the jointed levers I I, which, being attached to the arms or levers H H, which are secured to the shaft upon which the ratchet-wheels are secured, gives to them an intermittent motion, which motion is communicated to the driving-wheels through the gear-wheels E and F, and axle C, by which the intermittent reciprocating motion of the levers is converted into a continuous rotary motion of the wheels.

I have described the arrangement of the parts, for converting the reciprocating motion into a continuous rotary motion, as applicable only to velocipedes; but it is apparent that it may be used for turning-lathes, and various other devices, with equal facility.

Having thus described my invention,

What I claim, and desire to secure by Letters Patent, is—

1. The combination of the jointed levers I, arms or levers H, slides I', springs a, connecting-rod K, levers L, and ratchet-wheels G, for converting the reciprocating motion into a continuous rotary motion, substantially as and for the purpose set forth.

2. The arrangement of the swinging portion b of the levers L, substantially as and for the purpose set forth.

In testimony whereof, I have signed my name to this specification, in the presence of two subscribing witnesses.

C. A. HARPER.
